METHOD AND APPARATUS FOR PRODUCING
POWER

Edward T. Turner, Dayton, Ohio

Application March 6, 1939, Serial No. 259,982

20 Claims. (Cl. 60—73)

This invention relates to a method and apparatus for producing power and the main object of the invention is to provide such a method and apparatus which will utilize a larger part of the steam energy than is possible in the usual steam plant and will thus reduce the amount of steam required to produce a given amount of power and thereby reduce fuel consumption.

A further object of the invention is to provide a simple and efficient method and apparatus for preheating feed water and imparting thereto a high pressure which will enable it to enter a boiler against boiler pressure.

A further object of the invention is to provide means for adiabatically compressing a mixture of the exhaust steam and feed water, raising the temperature of the mixture during the period of compression, and simultaneously condensing steam in the mixture, thereby utilizing heat of the exhaust steam which would otherwise go to waste in the condenser.

A further object of the invention is to provide means for effecting a steam power cycle which will approach the Carnot cycle in efficiency.

A further object of the invention is to provide means for effecting the compression of a mixture of steam and feed water without the use of moving parts.

Other objects of the invention may appear as the apparatus is described in detail.

In the accompanying drawings Fig. 1 is a diagrammatic view of an apparatus embodying my invention; Fig. 2 is a longitudinal sectional view of the device for mixing low pressure steam with water and compressing said mixture; Fig. 3 is a longitudinal sectional view through the feed water injector; and Figs. 4 and 5 are temperature entropy diagrams.

In the ordinary steam plant only a relatively small part of the energy of the steam is utilized in the production of power, a large part of this energy being lost. For the purpose of utilizing a larger part of the energy of the steam I have devised a method whereby steam exhausted from a power unit is mixed with feed water and the mixture compressed to impart high pressure thereto, to condense the steam therein and impart high temperature to the mixture, the feed water being then converted into steam at said high pressure and returned to the power unit, and a portion of the exhaust steam being separated from the mixture, prior to the compression thereof, and if desired utilized to operate a second power unit.

In its preferred form my method comprises

introducing steam from a steam generator, such as a boiler, into a high pressure power unit, expanding the steam in said power unit and exhausting the same therefrom at a relatively low pressure. This expansion is preferably effected adiabatically but this is not essential. This low pressure steam is then slightly expanded and mixed with feed water and the steam in said mixture is then further expanded to impart additional velocity energy to the mixture. While the mixture is thus moving at high velocity a portion of the steam is separated from the mixture and the remaining portion of the mixture, that is, the feed water and the unseparated steam, is compressed to a pressure sufficient to enable the same to enter the steam boiler and during its compression the steam entrained in said feed water is condensed and its heat transferred to the feed water, thereby raising the feed water to a high temperature prior to its introduction into the boiler. Preferably the separated portion of the steam is further utilized and for this purpose it may be compressed adiabatically to a pressure preferably approaching the initial pressure of the low pressure steam and delivered to a low pressure power unit in which it is expanded to a very low pressure and is then condensed at said low pressure, and, if desired, the condensate may be utilized as the feed water and mixed with the first mentioned portion of the low pressure steam.

While the foregoing method and the apparatus for performing the same are designed primarily for converting water into steam and utilizing the steam, the use of steam is not essential and various elastic fluids may be substituted therefor. Therefore the term "steam" as herein used is intended to include any such elastic fluid.

The apparatus for performing the method may take various forms and the particular apparatus here illustrated comprises a high pressure power unit 10 and a low pressure power unit 11. The terms "high pressure" and "low pressure" are here used merely to designate the difference in pressure at which the two power units operate and the power units may be operated at any desired pressure so long as one operates at a lower pressure than the other. The high pressure power unit 10 is connected by a pipe 12 with a steam generator, such as a boiler 13, and the steam which is delivered from the boiler to the power unit at high pressure is expanded through the power unit and is exhausted therefrom through an exhaust conduit 14. The exhaust

conduit 14 is connected with a device for mixing the lower pressure steam with feed water and for separating a portion of the steam therefrom and separately compressing the separated steam and the remaining mixture of steam and feed water. In the preferred construction this device comprises a tubular structure 15 having a tapered longitudinal bore in which an elongate tapered core 16 is arranged to form between the same and the wall of the structure 15 an annular passageway, the larger end portion of said annular passageway constituting a mixing chamber as shown at 17. Connected with said tubular structure at said larger end thereof is a head 18 having an opening 19 which is connected at one end with the exhaust conduit 14 and communicates at its other end with the mixing chamber 17. The larger end of the core 16 extends into this opening 19 and is tapered, as shown at 20, to provide between the same and the wall of the opening 19 an annular tapered passageway 21 which constitutes the steam inlet for the mixing chamber 17. A cross bar 22 secured to the head 18 is connected with and constitutes a support for the core 16. The head 18 is provided with an annular channel 23 which is connected by a pipe 24 with a source of supply for feed water. This annular channel is connected with the mixing chamber by a passageway 25 which constitutes a feed water inlet for the mixing chamber and preferably is annular in form and extends entirely about the steam inlet 21.

The steam inlet 21 is so shaped that the low pressure steam passing through the same will be slightly expanded to impart velocity energy thereto, so that the incoming steam will carry feed water with it into and through the mixing chamber 17, in which the steam and feed water are intimately mixed. That portion of the annular passageway, through the tubular structure 15, which lies just beyond the mixing chamber 17 is shaped to provide an expansion nozzle 26 in which the steam in the mixture of steam and water is expanded to impart a high velocity to the mixture. The mixture at this high velocity is discharged from the expansion nozzle through a directing chamber 27 which is arranged to direct the mixture of steam and water along and in contact with the tapered surface of the core 16 and that portion of the annular passageway in the tubular structure which lies beyond the directing chamber is enlarged, as shown at 28, to form a separating chamber. As the mixture of steam and water moves along the tapered surface of the core the mixture is compressed to a more compact form which results in a portion of the steam being squeezed out of the mixture and discharged laterally into the separating chamber 28, so that the separated steam moves along the outer wall of the annular separating chamber and the remainder of the mixture, that is, the feed water and the entrained steam, moves along the inner wall of the separating chamber. The separation does not materially reduce the velocity energy of the steam or water and both the separated steam and the remainder of the mixture move through the separating chamber at high velocity.

The mixture of steam and feed water passes beyond the small end of the core 16 into a compression nozzle 29. As here shown, the compression nozzle is separate from the passageway through the tubular separator 15 and is mounted in the smaller end portion of that passageway and spaced from the walls thereof. In the pres-

ent instance this compression nozzle communicates with and is supported by a pipe 30 which leads to the boiler 13. As the mixture of steam and water passes through the compression nozzle 5 it is adiabatically compressed and the velocity energy of the mixture converted into pressure energy and at the same time the steam which is contained in the mixture is condensed and the water heated to a high temperature. The pressure 10 thus imparted to the feed water, which now includes the condensed steam, is sufficient to deliver the feed water through the pipe 30 into the boiler, against boiler pressure, thus the feed water at high pressure and high temperature is 15 delivered to the boiler and again converted into steam.

The design of the apparatus may be such as to raise the temperature of the feed water substantially to the temperature of the boiler water, that is, the temperature of vaporization at boiler pressure, and under such a condition the steam in the mixture would be fully condensed when the compression pressure equalled boiler pressure. By using a smaller ratio of steam to water in the 25 mixture which is passed through the compression nozzle the steam in the mixture may be fully condensed at a pressure somewhat below boiler pressure. When this is done it will usually be desirable to further heat the feed water by the application of external heat, as by a heater 30a. However, it may be desirable to effect condensation at a pressure below boiler pressure under some 30 circumstances, such as when external heat is available for the purpose at low cost.

35 The steam which is separated from the mixture in the tubular structure may be discharged to waste or utilized in any desired manner. In the present apparatus the space between the compression nozzle 19 and the wall of the tubular structure 15 is shaped to form a steam compression chamber 31 which receives the separated steam from the separating chamber at high velocity and compresses the same adiabatically to a pressure which preferably approximates the pressure at which the low pressure 40 steam is exhausted from the high pressure turbine. The separated steam at this pressure is delivered from the compression chamber into a discharge chamber 32 from which it passes through a conduit 33 to the low pressure turbine 11 in which it is expanded adiabatically to a very low pressure and is exhausted through a conduit 34 to a condenser 35. The condensate may be withdrawn from the condenser and delivered to 45 the mixing chamber 17, as feed water, at substantially condenser temperature.

50 The condensate may be transferred from the condenser to the mixing chamber in any suitable manner but I prefer to employ an injector for this purpose and to actuate the injector by 55 steam withdrawn from the exhaust conduit 14. For this purpose I have provided an injector 37, connected by a pipe 38 with the condenser 35, and a compression nozzle 39 which is connected by the feed water supply pipe 24 with the annular channel 23 in the head 18. Extending into 60 the mixing chamber 37 of the injector is an expansion nozzle 40 which is connected by a pipe 65 41 with the exhaust conduit 14 in advance of the mixing chamber. The pipe 41 is of small capacity so that a small portion only of the low pressure steam is withdrawn from the exhaust conduit. As this steam passes through the expansion nozzle 40 its pressure energy is converted 70 into velocity energy which serves to draw the 75

condensate from the condenser 35 into the mixing chamber 37 and to there mix the same with the steam. This mixture is then discharged into the compression nozzle 39 where its velocity energy is converted into pressure energy and the mixture of steam and condensate, or feed water, is delivered through the pipe 24 and channel 23 to the mixing chamber 17.

The amount of feed water required by the boiler will fluctuate under different conditions of operation, such as variations in the load imposed upon the power elements, and when the flow of feed water through the tubular structure 15 is reduced the quantity of steam condensed in the steam compression nozzle 29 is also reduced and as a result the steam pressure in the separating chamber 28 will tend to rise and may reach a pressure which will interfere with the proper functioning of the apparatus. To avoid this and to maintain an approximately uniform pressure in the separating chamber I have provided means controlled by the pressure in the separating chamber to by-pass a portion of the low pressure steam from the exhaust conduit 14 directly to the conduit 33 through which the separated steam is discharged from the tubular structure 15 and which in the present instance leads to the low pressure power unit. As here shown, this bypass comprises a conduit 42 which is provided with a valve 43 to control the flow of steam through the same. The valve is actuated by a lever 44 connected at one end with the stem 45 of the valve and at its other end with a bellows 46 which is connected by a pipe 47 with the separating chamber 28, the arrangement being such that when the pressure in the separating chamber rises to an objectionable extent this pressure will act upon the bellows 46 to open the valve 43 and thus by-pass a portion of the steam sufficient to maintain the steam in the separating chamber at the desired pressure.

As will be apparent from the foregoing description a large part of the heat and pressure energies of the exhaust steam, which is discharged from the high pressure power unit, is utilized, a portion of this steam serving to heat and impart high pressure to the feed water, and another portion of this steam serving to operate the low pressure power unit, after which it may be condensed and the condensate utilized as the feed water which is delivered to the mixing chamber and mixed with the first mentioned portion of the low pressure steam. Thus the heat of a portion of the steam exhausted from the high pressure power unit is retained in the compressed mixture of steam and feed water instead of being dissipated in the condenser as is customary and as a result the amount of steam and therefore the amount of fuel required to produce a given amount of power is substantially reduced, with a corresponding reduction in the cost of operation. As illustrative of this increase in the useful energy of the steam I have shown in Fig. 4 a temperature entropy diagram showing the relation of useful energy to total energy, both in an ordinary steam plant and in the present apparatus, said diagram being based on the use of dry and saturated steam. As there shown, the useful energy derived from an ordinary steam plant is represented by the area *acefa* and the waste energy is represented by the area *afgia*. The useful energy derived from the use of the present apparatus is represented by the area *cefbc* while the waste energy resulting from the use of this apparatus is represented by the area *bfghb*. The

efficiency of the apparatus is indicated by the ratio of the useful area to the total area, that is, the sum of the useful and waste areas, and it will be noted that the ratio of the useful area to the wasted area resulting from the use of the present apparatus is much larger than the ratio of the useful energy to the wasted energy in the ordinary apparatus, thus clearly indicating materially increased efficiency in the present apparatus.

The diagram of Fig. 4 assumes that the steam is not fully condensed in the mixture until the mixture is compressed to boiler pressure. When the condensation of the steam is effected at a pressure somewhat below boiler pressure the diagram is modified, as shown in Fig. 5. There the useful area of the ordinary steam plant is represented by the area *acc'efa* and the wasted energy is represented by the area *afgia*. The useful energy derived from the present apparatus under the conditions last named is represented by the area *cc'efbc* and the wasted energy is represented by the area *bfghb*. And again it will be noted that the ratio of useful energy to wasted energy is much greater in the present apparatus than it is in the ordinary steam plant.

While I have described my preferred method and have shown and described one form of apparatus for performing that method I wish it to be understood that I do not desire to be limited to the details thereof as various modifications may occur to a person skilled in the art.

Having now fully described my invention, what I claim as new and desire to secure by Letters Patent, is:

1. A method of producing power which comprises expanding high pressure steam through a power unit to a lower pressure, mixing said steam at said lower pressure with feed water and expanding the steam to impart velocity energy to said mixture of steam and water, separating a portion only of said steam from said mixture at high velocity, separately utilizing said separated steam, compressing the remainder of said mixture to convert velocity energy thereof into pressure energy and to condense the steam which is entrained in said feed water, converting the mixture of feed water and condensed steam into high pressure steam, and utilizing said high pressure steam.

2. A method of producing power which comprises expanding high pressure steam through a power unit to a lower pressure, mixing said steam at said lower pressure with feed water and expanding said steam to impart velocity energy to said mixture of steam and water, separating a portion only of said steam from said mixture at high velocity, compressing the remainder of said mixture to convert velocity energy thereof into pressure energy and to condense the steam which is entrained in said feed water, converting the mixture of feed water and condensed steam into high pressure steam, condensing the separated steam, utilizing the condensate as feed water and mixing the same with the steam from said power unit.

3. A method of producing power which comprises expanding high pressure steam through a high pressure power unit to a lower pressure, mixing said steam at said lower pressure with feed water, expanding the steam in said mixture to impart velocity energy to the mixture of steam and water, separating a portion of the steam from said mixture, compressing the separated steam to convert velocity energy thereof into

pressure energy, expanding said separated steam through a low pressure power unit to a lower pressure, compressing the remainder of said mixture of water and unseparated steam to convert velocity energy thereof into pressure energy and to condense said steam, and then converting said mixture of feed water and condensed steam at high pressure into steam.

4. A method of producing power which comprises expanding high pressure steam through a high pressure power unit to a lower pressure, mixing said steam at said lower pressure with feed water, expanding the steam in said mixture to impart velocity energy to the mixture of steam and water, separating a portion of the steam from said mixture, compressing the remainder of said mixture adiabatically to convert velocity energy thereof into pressure energy and to condense the unseparated steam, converting the mixture of feed water and condensed steam into high pressure steam, compressing the separated steam adiabatically to convert velocity energy thereof into pressure energy, expanding said separated steam adiabatically through a low pressure power unit to a lower pressure, condensing the steam exhausted from said low pressure power unit and utilizing the condensate as the feed water which is mixed with steam from said high pressure power unit.

5. In an apparatus of the character described, a power unit, means for delivering high pressure steam to said power unit and exhausting the same therefrom at a lower pressure, means for mixing said low pressure steam with and expanding the same in said water to impart velocity energy to the mixture of steam and water, means for separating a portion of the steam from said mixture at said velocity and delivering the separated steam to a point of use, means for compressing the mixture of water and unseparated steam to a higher pressure, and means for utilizing the same at said high pressure.

6. In an apparatus of the character described, a power unit, means for delivering high pressure steam to said power unit and exhausting the same therefrom at a lower pressure, means for mixing said low pressure steam with feed water and expanding said steam in said feed water to impart velocity energy to the mixture of steam and feed water, a condenser, means for separating a portion of the steam from said mixture and delivering the same to said condenser, means for compressing the mixture of feed water and unseparated steam to a high pressure, means for converting said feed water into steam at said high pressure, and means for delivering the condensate from said condenser to said mixing means.

7. In a power apparatus comprising a high pressure power unit and a low pressure power unit, means for delivering steam to said high pressure power unit and exhausting the same therefrom at a lower pressure, means for mixing said steam at said low pressure with feed water and expanding said steam in said feed water to impart velocity energy to the mixture of steam and feed water, means for separating a portion of said steam from said mixture and converting velocity energy thereof into pressure energy, means for delivering said separated steam to said low pressure power unit and exhausting the same therefrom at a lower pressure, means for converting velocity energy of said mixture of feed water and unseparated steam into pressure

energy, and means for converting said mixture into steam at said pressure.

8. In a power apparatus comprising a high pressure power unit and a low pressure power unit, means for delivering steam to said high pressure power unit and exhausting the same therefrom at a lower pressure, means for mixing said steam at said low pressure with feed water to impart velocity energy to the mixture of steam and feed water, means for separating a portion of said steam from said mixture and converting velocity energy thereof into pressure energy, means for delivering said separated steam to said low pressure power unit and exhausting the same therefrom at a lower pressure, a condenser connected with said low pressure power unit to receive the steam therefrom, means for delivering the condensate from said condenser to said mixing means, means for converting velocity energy of said mixture of feed water and unseparated steam into pressure energy, and means for converting said mixture into steam at said pressure.

9. In a power apparatus comprising a high pressure power unit and a low pressure power unit, means for delivering steam to said high pressure power unit and exhausting the same therefrom at a lower pressure, means for mixing said steam at said lower pressure with feed water and expanding said steam in said feed water to impart velocity energy to the mixture of steam and feed water, means for separating a portion of said steam from said mixture and converting velocity energy thereof into pressure energy, means for delivering said separated steam to said low pressure power unit and exhausting the same therefrom at a lower pressure, a condenser connected with said low pressure power unit to receive the steam therefrom, an injector, means for connecting said injector with said condenser and with said mixing means, means for delivering a portion of said low pressure steam to said injector, means for converting velocity energy of said mixture of feed water and unseparated steam into pressure energy, and means for converting said mixture at said pressure into steam.

10. In a power apparatus comprising a high pressure power unit and a low pressure power unit, means for delivering steam to said high pressure power unit and exhausting the same therefrom at a lower pressure, means for mixing said steam at said lower pressure with feed water and expanding said steam in said feed water to impart velocity energy to the mixture of steam and feed water, means for separating a portion of said steam from said mixture and converting velocity energy thereof into pressure energy, means for delivering said separated steam to said low pressure power unit and exhausting the same therefrom at a lower pressure, means for converting velocity energy of said mixture of feed water and unseparated steam into pressure energy, means for converting said mixture into steam at said pressure, and means controlled by pressure in said separating means for by-passing a portion of said low pressure steam to said low pressure power unit in advance of said mixing means.

11. In an apparatus of the character described, a power unit, means for supplying steam under pressure to said power unit and exhausting the same therefrom at a lower pressure, a mixing chamber, a conduit to conduct said low pressure steam from said power unit to said mixing chamber, said mixing chamber having an inlet for wa-

ter, an expansion chamber arranged beyond and communicating with said mixing chamber, a separating chamber arranged to receive a mixture of steam and water from said expansion chamber and to separate a portion of the steam from said mixture, a compression chamber to compress the separated steam and impart pressure energy thereto, means for utilizing said separated steam at said pressure, a compression nozzle arranged to receive from said separating chamber the remaining portion of said mixture of water and steam and compress the same to a high pressure, and means for converting said mixture into steam at said high pressure.

12. In an apparatus of the character described, a power unit, means for supplying steam under pressure to said power unit and exhausting the same therefrom at a lower pressure, a mixing chamber, a conduit to conduct said low pressure steam from said power unit to said mixing chamber, said mixing chamber having an inlet for water, an expansion chamber arranged beyond and communicating with said mixing chamber, a separating chamber arranged to receive a mixture of steam and water from said expansion chamber and to separate a portion of the steam from said mixture, a compression chamber to compress the separated steam and impart pressure energy thereto, a second power unit, a conduit for delivering said separated steam from said compression chamber to said second power unit, a compression nozzle arranged to receive from said separating chamber the remaining portion of said mixture of water and steam and to compress the same to a higher pressure, and means for converting said mixture to steam at said high pressure.

13. In an apparatus of the character described, a power unit, means for supplying steam under pressure to said power unit and exhausting the same therefrom at a lower pressure, a mixing chamber, a conduit to conduct said low pressure steam from said power unit to said mixing chamber, said mixing chamber having an inlet for water, an expansion chamber arranged beyond and communicating with said mixing chamber, a separating chamber arranged to receive a mixture of steam and water from said expansion chamber and to separate a portion of the steam from said mixture, a compression chamber to compress the separated steam and impart pressure energy thereto, a second power unit, a conduit for delivering said separated steam from said compression chamber to said second power unit, a compression nozzle arranged to receive from said separating chamber the remaining portion of said mixture of water and steam and to compress the same to a high pressure, means for converting said mixture to steam at said high pressure, a by-pass connecting said conduits, a valve in said by-pass, and means controlled by pressure in said separating chamber for actuating said valve.

14. In an apparatus of the character described, a power unit, means for supplying steam under pressure to said power unit and exhausting the same therefrom at a lower pressure, a mixing chamber, a conduit to conduct said low pressure steam from said power unit to said mixing chamber, said mixing chamber having an inlet for water, an expansion chamber arranged beyond and communicating with said mixing chamber, a separating chamber arranged to receive a mixture of steam and water from said expansion chamber and to separate a portion of the steam

from said mixture, a compression chamber to compress the separated steam and impart pressure energy thereto, a compression nozzle arranged to receive from said separating chamber the remaining portion of said mixture of water and steam and compress the same to a high pressure, means for converting said mixture into steam at said high pressure, a condenser, means for conducting said separated steam from said compression chamber to said condenser, an injector having an inlet connected with said condenser, and having an outlet connected with said mixing chamber, and means for delivering a portion of the low pressure steam from said power unit to said injector.

15. A method of producing power which comprises expanding high pressure steam through a power unit to a lower pressure, mixing water with said steam at said lower pressure, expanding said steam in said water to impart velocity energy to the mixture of steam and water, separating a portion of the steam from said mixture at said high velocity, converting the velocity energy of said separated steam into pressure energy and utilizing the same at said pressure; compressing the remaining portion of said steam and water to a high pressure and condensing the steam in the water, and converting the water and condensed steam at said high pressure into steam.

16. A method of producing power which comprises expanding high pressure steam through a power unit to a lower pressure, expanding said steam at said lower pressure to impart velocity energy thereto, mixing said steam with water to impart velocity energy to the water, separating a portion of the steam from the mixture of steam and water at said velocity and compressing the remaining portion of said mixture of steam and water to a high pressure and condensing the steam in the water, converting the water and condensed steam at high pressure into steam and separately utilizing said separated steam.

17. In an apparatus of the character described, a power unit, means for supplying steam under pressure to said power unit and exhausting the same therefrom at a lower pressure, a mixing chamber, a conduit to conduct said low pressure steam from said power unit to said mixing chamber, said mixing chamber having an inlet for water, means for imparting velocity energy to the mixture of steam and water, a separating chamber to receive said mixture and separate a portion of the steam from said mixture, a conduit through which the separated steam is discharged to a point of use, means for compressing the remainder of said mixture to a high pressure and condense the steam in said mixture, means for converting said mixture at high pressure into steam, a by-pass connecting said conduits, a valve in said by-pass, and means controlled by pressure in said separating chamber for actuating said valve to divert excess steam from the first mentioned conduit to the last mentioned conduit.

18. In an apparatus of the character described, a power unit, means for supplying steam under pressure to said power unit and exhausting the same therefrom at a lower pressure, a tubular structure having near one end thereof a mixing chamber, means for connecting said mixing chamber with said power unit to receive the steam therefrom at said lower pressure, means for supplying water to said mixing chamber, said tubular structure having therein beyond said mixing chamber an expansion chamber to con-

vert pressure energy of said steam into velocity energy, a separating chamber to receive the mixture of steam and water at high velocity and separate a portion of the steam from said mixture, and also having a compression chamber arranged to receive separated steam from said separating chamber and having means for discharging said separated steam at a higher pressure to a point of use, and a compression nozzle arranged within said tubular structure to receive the remaining portion of said mixture of steam and water and convert the velocity energy thereof into pressure energy.

19. In an apparatus of the character described, a power unit, means for supplying steam under pressure to said power unit, and exhausting the same therefrom at a lower pressure, an elongate structure having a tapered passageway, means for connecting the larger end of said passageway with said power unit to receive said low pressure steam therefrom, means for supplying water to said larger end of said passageway, a core supported in and spaced from the wall of said passageway, said passageway and said core being shaped and arranged to provide in said structure a mixing chamber at the larger end of the passageway, an expansion chamber beyond said mixing chamber, a separating chamber beyond said expansion chamber, a compression chamber beyond said separating chamber having means for discharging said separated steam at high pressure to a point of use, a compression nozzle arranged in said compression chamber beyond said core, means for connecting said compression

10 chamber with a second power unit, and a heater connected with said compression nozzle.

20. In an apparatus of the character described, a high pressure power unit and a low pressure power unit, means for delivering steam to said high pressure power unit and exhausting the same therefrom at a lower temperature, a tubular structure having at one end an inlet for steam connected with said high pressure power unit and an inlet for water, an elongate tapered core supported in said structure, said structure and said core being shaped and arranged to form between the same an annular tapered passageway having adjacent said inlets a chamber in which the steam and water are mixed, a part forming an expansion nozzle to expand said steam and impart velocity energy to the mixture of steam and water, a part beyond said expansion nozzle arranged to direct said mixture of steam and water along and close to the tapered surface of said core, a separating chamber beyond said directing part in which a portion of the steam is separated from the mixture of steam and water, a part beyond said separating chamber to compress the separated steam to a higher pressure, means for delivering the steam which has been so compressed to said low pressure power unit, a compression nozzle arranged in said compression chamber in line with the smaller end of said core to receive the remaining portion of said steam and water and compress the same to a relatively high pressure, and means for delivering the compressed mixture to a point of use.

EDWARD T. TURNER.
